UNITED STATES PATENT OFFICE

148,586

DESIGN FOR A JEWEL CASE

Daniel J. Slater, St. Paul, Minn.

Application August 26, 1946, Serial No. 132,861

Term of patent 14 years

(Cl. D86—9)

To all whom it may concern:

Be it known that I, Daniel J. Slater, a citizen of the United States, residing at St. Paul, in the county of Ramsey and State of Minnesota, have invented a new, original, and ornamental Design for a Jewel Case, of which the following is a specification, reference being had to the accompanying drawing, forming a part thereof.

In the drawing:

Figure 1 is a perspective view of a jewel case showing my new design;

Fig. 2 is a plan view of the same;

Fig. 3 is a front elevational view of the same, and

Fig. 4 is an end elevational view of the same.

I claim:

The ornamental design for a jewel case, as shown.

DANIEL J. SLATER.
